(57) **CLAIM**

The ornamental design for a drum stick, as shown and described.

DESCRIPTION

FIG. 1 is a front perspective view of a drum stick, showing my new design;

FIG. 2 is a front elevation view thereof, the rear elevation view being a mirror image thereof;

FIG. 3 is a left elevation view thereof, the right elevation view being a mirror image thereof;

FIG. 4 is a top plan view thereof; and,

FIG. 5 is a bottom plan view thereof.

The broken lines shown in the drawings depict portions of the drum stick that form no part of the claimed design.
